UNITED STATES PATENT OFFICE.

CORNELIUS LORON EDWARDS, OF NEWARK, NEW YORK.

BRIDLE-BIT.

SPECIFICATION forming part of Letters Patent No. 392,998, dated November 20, 1888.

Application filed July 16, 1888. Serial No. 280,073. (No model.)

To all whom it may concern:

Be it known that I, CORNELIUS LORON EDWARDS, of Newark, in the county of Wayne and State of New York, have invented certain 5 new and useful Improvements in Bridle-Bits; and I do hereby declare the following to be a full, clear, and exact description of the invention, such as will enable others skilled in the art to which it appertains to make and use the 10 same.

My invention relates to an improvement in bridle-bits, and has for its object to provide a bit composed of several parts removably and adjustably secured together.

15 A further object is to provide a bit which may be readily adapted to horses having different-shaped mouths.

20 A further object is to furnish a bridle-bit which shall be simple in construction, effective in operation, and cheap to manufacture.

With these objects in view my invention consists in certain novel features of construction and peculiar combinations and arrangements of parts, as will be hereinafter set forth, 25 and pointed out in the claims.

In the accompanying drawings, Figure 1 is a view showing the parts separated. Fig. 2 is a view of the parts assembled. Fig. 3 is a view showing the central extension-piece removed.

30 A indicates a center piece of elliptical form, and provided at each end and in its center with screw-threaded sockets a, b, and c. The end sockets, a b, are intended to receive the screw-threaded shanks of eyelets d, which are 35 screwed into the central piece, A, as shown in Fig. 2. Attached to the eyelets d d by means of swivel-joints are two inwardly-tapering links, B C, perforated at their larger ends for the reception of metal rings e e, which serve 40 for attachment of the reins.

Two upwardly-extending levers, D E, provided with loops at their lower ends, are looped about the links B C near the outer extremities of the latter. The levers B C may be made of 45 leather, having the loops f made of sufficient size to permit a free movement of the links through them; and the upper portions of said levers may be tightly wound with cord or wire to produce a tubular form. At the upper extremities of the levers D E eyelets g are 50 connected by swivel-joints, and serve for

the attachment of the overdraw-strap F and nose-strap G. (Shown in dotted lines in Fig. 2.) Making the side levers, D E, of leather and providing them with eyelets at their upper ends, connected by swivel-joints, will be found to be of great advantage over the usual solid metallic side levers, as they act upon the trifacial nerves without chafing or cutting the sides of the horse's mouth, and the straps attached to the swiveled eyelets will have free movement independent of the levers themselves, and therefore will not cause the lever to twist and turn and be unnecessarily forced against the sides of the horse's mouth. These 65 levers may be made of metal, if desired. The perforation e in the center of the central piece, A, is adapted for the reception of the screw-threaded shank of a tongue or extension-piece, h, made preferably of oval shape.

70 The mouths of horses vary in shape, being more or less concave or having no concavity at all. In order, therefore, to reach the maxillary nerves in the operation of the bit, the tongue or extension h is provided, and is 75 adapted to be screwed more or less into the central piece, A, corresponding to the degree of concavity of the horse's mouth. In case the mouth of the horse upon which the bit is to be used has no concavity, the tongue or extension h may be entirely dispensed with, as shown in 80 Fig. 3.

If it be desired to make the bit longer or shorter to suit different horses, the eyelets e may be readily screwed into the center piece 85 to a greater or less degree, as desired. By constructing the bit as above set forth the parts are easily adjusted, have a free and easy movement when the bit is operated, and are not apt to injure the mouth of the horse. They 90 may also be separated and packed in very small space for transportation, and easily and quickly put together when desired for use.

Many slight changes might be made in the constructive details of my invention without 95 departing from the spirit thereof; hence I do not wish to limit myself to the precise details of construction herein set forth; but,

Having fully described my invention, what I claim as new, and desire to secure by Letters 100 Patent, is—

1. A bridle-bit consisting of a central piece,

outwardly-extending links, devices loosely connected to the links and adjustably connected to the central piece, and rings attached to the links at their free ends, substantially as set forth.

5 2. In a bridle-bit, the combination, with a center piece, of eyelets removably secured thereto, links swiveled to said eyelets, and rings attached to the free ends of the links, substantially as set forth.

10 3. In a bridle-bit, the combination, with a center piece, of links swiveled thereto, rings at the free ends of said links, side levers loosely carried by said links, and eyelets swiveled on

the free ends of said side levers, substantially 15 as set forth.

4. In a bridle-bit, the combination, with a central piece, links secured thereto, and rings attached to the links, of a detachable tongue or extension attached to the center piece, substantially as set forth.

20 In testimony whereof I have signed this specification in the presence of two subscribing witnesses.

CORNELIUS LORON EDWARDS.
